CLAIM

The ornamental design for lavatory fixtures, substantially as shown and described.

DESCRIPTION

FIG. 1 is a raised perspective view of an embodiment of lavatory fixtures showing a faucet and soap dispenser in one fixture and a hand dryer in the other larger fixture;
 FIG. 2 is a raised perspective view of the embodiment of the lavatory fixtures according to FIG. 1;
 FIG. 3 is a rear view of the embodiment of the lavatory fixtures according to FIG. 1;
 FIG. 4 is a right-side view of the embodiment of the lavatory fixtures according to FIG. 1;
 FIG. 5 is a left-side view of the embodiment of the lavatory fixtures according to FIG. 1;
 FIG. 6 is a front view of the embodiment of the lavatory fixtures according to FIG. 1; and,
 FIG. 7 is a bottom view of the embodiment of the lavatory fixtures according to FIG. 1.
 Any broken lines represent environmental structure and form no part of the claimed design.
